UNITED STATES PATENT OFFICE.

DAVID C. HULL, OF WESTFIELD, MASSACHUSETTS, ASSIGNOR TO THE UNITED STATES WHIP COMPANY, OF SAME PLACE.

DESIGN FOR A BUTT-LOAD FOR WHIPS.

SPECIFICATION forming part of Design No. 34,009, dated January 29, 1901.

Application filed December 27, 1900. Serial No. 41,289. Term of patent 7 years.

To all whom it may concern:

Be it known that I, DAVID C. HULL, a citizen of the United States of America, and a resident of Westfield, in the county of Hampden and State of Massachusetts, have invented and produced a certain new and useful Design for a Butt-Load for Whips, of which the following is a full, clear, and exact description.

Reference is to be had to the accompanying drawings, in which the load-piece of the new design is illustrated, and in which—

Figure 1 is a perspective view of the butt-load. Fig. 2 is a side view of the same. Figs. 3, 4, and 5 are cross-sectional views taken, respectively, on the lines 3 3, 4 4, and 5 5, Fig. 1, said views being on a scale somewhat larger than that on which Fig. 1 is drawn.

As shown in the drawings, the leading characteristic of my design consists in the butt-load for a whip, which at its butt portion *a* is cross-sectionally of the form of an

irregular octagon and which from said butt portion is tapered, wedge-like, upwardly gradually and uniformly until the upper end is cross-sectionally in the form of a thin rectangle, the butt end having imparted thereto the form of an inverted dome or hemispheroid, as indicated at *d*.

The plane surfaces 1 1 and 2 2 2 2, which constitute the sides of the cross-sectionally octagonal body, are merged into the perimetrical surface of the portion *d* in an encircling series of scallops *ff*.

Having now described my invention, what I claim, and desire to secure by Letters Patent, is—

The design of a butt-load for a whip substantially as shown and described.

DAVID C. HULL.
